CLAIM

We claim the ornamental design for a golf club shaft, as shown and described.

DESCRIPTION

FIG. 1 is a perspective view of a golf club shaft, showing a first embodiment of our new design;

FIG. 2 is another perspective view of a golf club shaft, showing the first embodiment of our new design;

FIG. 3 is a rear side elevation view thereof;

FIG. 4 is a front side elevation view thereof;

FIG. 5 is a left side elevation view thereof;

FIG. 6 is a right side elevation view thereof;

FIG. 7 is a perspective view of golf club shaft, showing a fourth embodiment of our new design;

FIG. 8 is another perspective view of a golf club shaft, showing the fourth embodiment of our new design;

FIG. 9 is a rear side elevation view thereof;

FIG. 10 is a front side elevation view thereof;

FIG. 11 is a left side elevation view thereof; and,

FIG. 12 is a right side elevation view thereof.

In FIGS. 7 through 12, a lower portion of the shaft is lined for black and upper portion of the shaft is lined for copper. In FIGS. 7 through 12, lower and upper portions of the shaft are line for contrasting colors.

The broken line showing of a grip and club head is for illustrative purposes only and forms no part of the claimed design.

UNITED STATES PATENT AND TRADEMARK OFFICE
CERTIFICATE OF CORRECTION

PATENT NO. : Des 431,274
DATED : September 6, 2000
INVENTOR(S) : Phillip Besnard et al.

Page 1 of 1

It is certified that error appears in the above-identified patent and that said Letters Patent is hereby corrected as shown below:

Title page.

After the description of FIG. 12, delete "In FIGS. 7 through 12, a lower portion of the shaft is lined for black and an upper portion of the shaft is lined for copper. In FIGS. 7 through 12, lower and upper portions of the shaft are line for contrasting colors." and replace it with -- In FIGS. 7 through 12, lower and upper portions of the shaft are lined for contrasting colors. --.
